UNITED STATES PATENT OFFICE

ERNEST L. SMITH, OF SANTA CRUZ, CALIFORNIA, ASSIGNOR TO RINGLETTE PERMANENT COMPANY, OF SAN FRANCISCO, CALIFORNIA, A CORPORATION OF CALIFORNIA

HAIR CURLER

Application filed June 20, 1928. Serial No. 286,809.

The invention forming the subject matter of this application relates to a device for hair waving and curling.

On the electrical hair waving or curling devices in use at present, it is necessary to employ a large number of electric conduits, one for each heating unit of the hair curling device. It is well known that during permanent waving or other hair curling, practically 10 the whole head is covered with hair curling units, and thereby it is usually necessary to surround the whole head with a large number of electrical conduits leading from the source of electricity, which are both inconvenient and inefficient.

The primary object of the invention is the provision of a hair curler which may be readily connected in series to the adjacent curler so that the number of electric conduits leading 20 from the source of electricity to the head is reduced to a pair of conduits.

A further object of the invention is the provision of a hair curling or waving device in which the electrical heating units are disposed inside of a spindle, upon which the hair 25 is wound.

A still further object of the invention is the provision of a clamping device which is adapted to firmly and securely grip the hair, 30 and which is adapted to firmly hold in place a spindle upon which the hair may be wound very tightly without causing the pulling of the hair or irritating of the human scalp, the spindle being held in place by the force of 35 the turning moment exerted thereon by the tightly wound hair.

Another object of the invention is the provision of a clamp for firmly securing the hair to a spindle upon which the hair is wound, 40 and in which an electrical heating element is disposed, said spindle being provided with sockets at the opposite ends thereof to receive the terminals of electric conduits, one end of the spindle being formed in the shape of a 45 ratchet for engaging a holding member upon said clamp, which holding member is so shaped as to act as a pawl, thereby holding the spindle in place against the unwinding tendency of the hair.

50 Another object of the invention is to pro-

vide a hair curler which is highly useful and simple in construction. Convenience of arrangement, lightness, and capability of manufacture at lower cost are further objects which have been borne in mind in the production and development of the invention.

With the above mentioned objects and other objects in view, the invention consists in the novel construction and combination of parts hereinafter described, illustrated in the 55 accompanying drawings, and set forth in the claims hereto appended, it being understood that various changes in the form, proportion, size, and minor details of construction within the scope of the claims may be resorted to 60 without departing from the spirit, or without sacrificing any of the advantages, of the 65 invention.

In the drawings—

Figure 1 is a side view of a plurality of 70 hair curlers connected with each other in series, and also showing the means for controlling the electric current for the heating elements of the hair curlers, the hair curlers being shown in operative position upon the 75 head;

Figure 2 is a perspective view of the assembly of the hair curler with the cover removed, showing the same in the position when the spindle is secured upon the clamp and showing the hair wound around the spindle;

Figure 3 is a perspective view of the cover for the electric curler;

Figure 4 is a plan view of the clamp, showing the same in a clamping position;

Figure 5 is a plan view of the clamp, showing the same in the open position thereof;

Figure 6 is a longitudinal view of the complete hair curler;

Figure 7 is a sectional side view of the 90 assembled hair curler, the section being taken on the line 7—7 of Figure 6; and

Figure 8 is a detail plan view of the spindle, showing the means thereon for holding the end of the hair thereon.

In carrying out my invention, I make use of a spindle, denoted in its entirety by the numeral 6, and a clamp, designated in its entirety by the numeral 7. The spindle 6 comprises a shank member 8, the cross-sectional 95

100

area of which uniformly decreases from the end toward the central portion of the shank. In other words, the shank is in the form of a circular body generated by the rotation of a curved line around the spindle's longitudinal axis. At one end of the shank is disposed an enlarged cylindrical head 9, and the other end of the shank 6 terminates in a ratchet head 11. The spindle is hollow, providing a centrally disposed axial bore 12 therein, into which a tube 13, preferably a porcelain tube, is secured. Inside of the porcelain tube is an electric heating coil 14 connected to sockets 15 disposed in the opposite ends of the porcelain tube 13 and adapted to receive a plug terminal 17 of a connecting wire 18 therein.

Upon the spindle is a plate 19 pivotally secured adjacent to an end of the shank 8 as at 21; said plate 19 substantially conforming to a portion of the circumference of the shank 8, with which portion it coacts. The pivoted end of the plate 19 is cut away as at 20, so as to allow the rotation of the plate around its pivot. The clamp 7 comprises a hinge plate 23, at one end of which is pivotally secured a clamping jaw 24. At the other end of said hinge plate 23 is similarly pivoted a second clamping jaw 26. The pivoted ends of the jaws 24 and 26 are provided with slots 27 for receiving the hinge plate 23 therein. The jaws are so disposed, relatively to each other, that when rotated in a clamping position as shown in Figure 4, the inside edges of the jaws are in close proximity to each other. The top face of each jaw is recessed adjacent to the inside edge thereof, so that when the jaws are in closed position, the recesses form a groove 25 of arcuate cross section, in which the spindle 6 is received.

Inside of the jaw 24 is fixedly secured a gripping member 28, preferably made of rubber, while the jaw 26 has a centrally disposed longitudinal groove 29 therein so disposed as to receive the gripping member 28 therein when the jaws are closed. The groove 29 is made so as to allow the snug fitting of the gripping plate 28 therein. The hair is pressed by the gripping plate into the groove 29 when the clamp is closed.

At the free end of the jaw 24 is pivotally secured a fastening plate 31 rotatable in a groove 32 in the free end of the jaw 24. Upon the free end of the fastening plate 31 is eccentrically pivoted, as at 33, a cam lever 34. The free end of the jaw 26 is provided with an end groove or recess 36, similar to that of 32, into which the plate 31 extends when the clamp is closed.

The hair is inserted between the jaws and the strand of hair inserted is spread along the edge of the gripping member 28, whereupon the jaws are rotated toward each other so that the gripping member 28 presses the strand of hair into the groove 29 and firmly holds the same therein. The fastening plate

31 is turned around its pivot so as to assume the position shown in Figure 4, in which position it is inserted into the recesses 32 and 36. The cam lever 34 is now turned to the position shown in Figure 4, engaging an indentation 37 in the corresponding edge of the jaw 26, upon which now the cam lever 34 exerts a pressure. After the cam lever 34 passes its center of rotation, then the fastening plate 31 and the cam lever 34 are prevented from accidental removal from the recesses 32 and 36, partly by the friction between the cam lever 34 and the outside edge of the jaw 26, and partly by the indentation 37 with which the eccentric portion of the cam lever is firmly engaged.

A substantially semi-cylindrical socket 38 is secured on one face of the jaw 24 by means of a screw 39, the screw being counter-sunk in the manner shown in Figure 7. One edge 85 of the socket 38 is dented outwardly and rebent as at 41 so as to cooperate with the ratchet head 11 for preventing the rotation of the latter. It is to be noted that the edge 41 of the socket 38 functions as a pawl.

The device is attached to the hair by the following method: A strand of moistened hair is inserted into the clamp, the clamp being in such position that the socket 38 thereon points away from the human scalp. The jaws 24 and 26 are made of bakelite or other insulating material so as to obviate the danger of burning or irritating the scalp. The strand of hair is properly spread over the gripping member 28, and then the clamp is fastened in place in the manner heretofore described.

It is to be noted that any pull exerted upon the hair, extending from the side of the clamp on which the socket 38 is located, will not be transmitted to the root of the hair while the clamp is held in position. The hair is so firmly gripped in the clamp that the possibility of pulling the hair thru the clamp is entirely obviated.

Now the free end of the strand of hair is inserted between the plate 19 and the shank 8 in the manner shown in Figure 8. As the plate 19 conforms to a portion of the circumference of the shank 8, the end of the hair will be held against the curved shank surface when the plate 19 is turned in the position shown in Figure 8. It is to be noted that the spindle 6 at this time is not secured upon the clamp 7. The spindle 6 is so positioned that the ratchet head 11 thereof is toward the end of the socket 38. The spindle is turned, thereby winding the hair thereon around the outside of the plate 19, thus still more firmly securing the end of the hair in place. When the hair is completely wound on the shank 8, the spindle assumes the position shown in Figure 2, the spindle being in the recess 25, and the ratchet head 11 thereof engaging the socket 38. The teeth of the ratchet and the

pawl 41 cooperate in such a manner as to act against the unwinding tendency of the hair upon the spindle. The winding of the hair is accomplished by the rotation of the spindle in the direction of the arrow shown in Figure 5 7. From the same figure, it will be clearly seen that any unwinding tendency of the hair will exert a turning moment in a counter-clockwise direction, viewing Figure 7, and thus will cause a still firmer engagement of 10 the serrations or teeth of the ratchet head 11 with the pawl 41.

In order to allow still further tightening and winding of the hair, recesses 42 are provided in the end face of the cylindrical head 15 9 and are disposed in diametrically opposite positions so that a key, having corresponding double prongs, (not shown) may be inserted thereinto, thus providing sufficient leverage 20 for still further tightening and winding the hair on the spindle. Any returning movement of the spindle is prevented by the engagement of the consecutive teeth or serrations of the ratchet head 11 with the pawl 41.

25 After the hair is wound, and the spindle is fastened in place on the clamp, a cover 43 is placed over the spindle. The cover 43 is a cylindrical cover made of resilient material, and its cross section is slightly more than a 30 semi-circle so that the same must be stretched while it is slid over the heads 9 and 11, but then it resiliently grips the heads 9 and 11, thereby being securely held in position.

After the desired number of hair curling 35 devices is attached to the hair in the position shown in Figure 1, then the connecting wires 18 are used for connecting the hair curling devices in series with each other. Each end of the connecting wire 18 is provided with 40 the plug terminal 17. It is to be noted on Figure 1 that the wires 18 are disposed alternately on the opposite sides of the devices, connecting the adjacent sockets 15 in series. The wire 18 is flexible so that it may assume 45 the shape shown at 44 for connecting the uppermost units of the two rows of hair curling devices shown in the illustration in Figure 1.

Now, the only connections that lead from 50 the outside source of electricity to the hair curling devices are the conduits 46, an end of each being provided with a similar plug terminal 17 for connecting to the first two units of the series of hair curling devices. The other ends of the conduits 46 are 55 secured to the respective terminals of a resistance box 47, which, in turn, is connected to the source of electricity by the conduits 48. The resistance box 47 is provided with a plurality of contact blocks 49 and a control 60 handle 51 of the usual construction so as to regulate the voltage in the heating elements 14, thereby preventing the creation of excessive heat when a small number of units are employed and connected in series, or preventing the reduction of the current below 65

the necessary voltage when a large number of curling devices or units is connected in series. The proper voltage for effecting the suitable heat of the electric heating elements 14 may be experimentally determined.

70 It will be recognized that a particularly facile device is provided to accomplish the above described method of curling the hair in a simple manner and in such a way as to eliminate the large number of electric conduits leading from the outside to the human head. The device combines light weight and facility in attaching the same to the hair, with a ruggedness of construction and positiveness of operation, especially adapting it 75 for its use.

80 It will also be recognized that in order to facilitate the use of the hair curler by unskilled persons, the cylindrical head 9 of the spindle 6 may be serrated similarly to the 85 ratchet head 11, and by securing another semi-cylindrical socket, similar to the socket 38, to the other end of the jaw 24, both ends of the spindle 6 may be similarly secured to the clamp 7.

90 I claim:

95 1. In a hair curling and waving device, a clamp for gripping the hair at a point near the scalp, said clamp comprising two jaws, a member for pivotally holding said jaws in coacting relation with each other, the hair being gripped between adjacent faces of opposing jaws, means for fastening said jaws in hair gripping position to prevent the 100 pulling of the hair therethrough, a shank for winding into a coil the length of hair extending from the clamp, a cover for said shank, and means for holding the shank on said clamp and releasably locking the same from rotation in one direction, the said 105 clamping jaws each having an arcuate longitudinal bevel at the upper portion of their cooperating clamping edges whereby a longitudinal groove is formed on the upper face of the clamp overlying the 110 gripping tongue, so that the shank and holding means therefor may be placed in close proximity to the scalp.

115 2. In a hair curling and waving device, a clamp for gripping the hair at a point near the scalp, said clamp comprising two jaws, a member for pivotally holding said jaws in coacting relation with each other, a gripping tongue extending from the clamping edge of one jaw, the clamping edge of the 120 other jaw having a corresponding groove therein, the hair being pressed by said gripping tongue into said groove, means for fastening said jaws in a gripping position to prevent the pulling of the hair therethrough, a shank for winding into a coil the length of hair extending from the clamp, a cover for said shank, and means for holding the shank on said clamp with the hair 125 coiled thereon and for releasably locking the 130

same from rotation in one direction, the said clamping jaws each having an arcuate longitudinal bevel at the upper portion of their cooperating clamping edges whereby a longitudinal groove is formed on the upper face of the clamp overlying the gripping tongue, so that the shank and holding means therefore may be placed in close proximity to the scalp.

3. A hair curling and waving device comprising a means for gripping the hair; means for winding into a coil under tension the length of hair extending from said gripping means without affecting the hair between the gripping means and the scalp; means for securing said winding means against unwinding rotation when the length of hair is completely wound thereon, and an electric heating element extending thru said winding means, said gripping means having a baffle to prevent heat from the heating element from reaching the scalp.

In testimony whereof I affix my signature.
